W. KIDD

GOLF CLUB

Filed May 24, 1923

Inventor
WILLIAM KIDD

By *Paul Paul & Moore*
ATTORNEYS

UNITED STATES PATENT OFFICE.

WILLIAM KIDD, OF MINNEAPOLIS, MINNESOTA.

GOLF CLUB.

Application filed May 24, 1923. Serial No. 641,135.

To all whom it may concern:

Be it known that I, WILLIAM KIDD, a citizen of the Kingdom of Great Britain, residing in Minneapolis, county of Hennepin 5 and State of Minnesota, U. S. A., have invented certain new and useful Improvements in Golf Clubs, of which the following is a specification.

The object of my invention is to provide 10 a golf club having a striking face which will firmly hold a golf ball against slipping or skidding when contact takes place between the face of the club and the cover of the ball, as when the ball and club face are 15 wet, and at the same time will not damage or mar the cover or paint on the ball.

A further object is to provide a non-skidding ball-striking face for the club head which will not add materially to the expense of manufacture but will be very effective 20 for the purpose designed.

A further object is to provide a non-skidding face which can be applied to a metal or wooden head as desired.

25 Other objects of the invention will appear from the following detailed description.

The invention consists generally in various constructions and combinations all as 30 hereinafter described and particularly pointed out in the claims.

In the accompanying drawings forming part of this specification,

Figure 1 is a perspective view of a metal 35 golf club head embodying my invention;

Figure 2 is a sectional view on the line 2-2 of Figure 1;

Figure 3 is a perspective view showing 40 my invention applied to the face of a wooden club head.

In the drawing, 2 represents the blade of a metal club head having at one end a shank 3 provided with a socket for the insertion 45 of the shaft 4. The striking face 5 of the club head is usually provided in clubs of this kind with a series of ribs or other projections designed to contact with the cover of the ball and impart a backward spin to the ball when it is struck by the iron; the 50 theory being that the ribs running transversely to the direction of flight of the ball strike the cover a glancing blow with the swing of the club and impart to the ball a rotary movement in a backward direction 55 while the loft or lay-back of the club face

provides for the lift or elevation of the ball from the ground. Sometimes in place of ribs running lengthwise of the club face, projections of various forms are provided having substantially the same function as 60 the ribs; namely, that of imparting a back-spin to the ball when it meets the striking face of the club. These ribs and projections of different kinds I have found to be objectionable as they tend to cut, scratch, or 65 otherwise mar the surface of the ball and its cover, throwing it out of its true spherical form and causing it to roll unevenly in putting. Furthermore, the use of projections or protuberances on the club face frequently damages the ball to such an extent 70 that it not only prevents it from putting well but interferes with its flight through the air.

In my invention, I have discarded entirely 75 all ribs, projections or protuberances of any kind and in place thereof, I provide a series of cup-shaped depressions or recesses 6 in the striking face of the club. These depressions are preferably circular in form 80 and rounded at the bottom and have flat areas or surfaces 7 between them as shown plainly in Figure 1; the depressions being formed by means of a drill or other suitable tool. I may provide any desired number 85 of the depressions in the face of the club arranging them in such relation that a narrow flat space is provided between the adjacent depressions and there are no sharp or rough surfaces to mar or damage the 90 cover of the ball.

The depressions are of suitable depth so 95 that when the striking face of the club contacts with the ball cover, there will be a certain degree of suction established, the ball being flattened partially by contact with the club so that a considerable number of the depressions will be under the flattened area of the ball; the number depending of course upon the speed of contact of the striking face with the ball or the force of the blow. The edges of the depressions may slightly mark the ball cover, indicating the points of contact of the ball with the club 100 face but the suction established between the cover and the depressions will firmly hold the ball, preventing it from skidding or sliding and interfering with the success of the shot. At the same time, the ball cover 105 will not be damaged or marred as it frequently 110

quently is when a grooved or ribbed club face is used or one having a series of projections or protuberances thereon. The depressions may be of any suitable depth preferably as shown in the drawing, as I have found from actual use of the club that the best results are obtained with depressions of the relative arrangement and size shown. The depressions are preferably arranged across the full width of the club-striking face and a sufficient distance longitudinally thereon to insure contact of the edges of the depressions with the ball.

In Figure 3, I have shown the invention applied to a wooden club head 8 having a striking face 9 provided with a recess 10 in which a plate 11, preferably metallic, is secured by suitable means such as screws 12. This plate has a series of depressions 6^a therein corresponding to those shown in Figures 1 and 2; some of the depressions at the ends of the plate being of smaller diameter than those near the middle portion thereof, the adjacent depressions being spaced apart forming the flat surface between them as shown and described with reference to Figure 1. This device applied to a wooden club head insures accuracy of shot, prevents skidding of the ball on the face of the club, particularly when wet, and holds it firmly under normal conditions of use. Furthermore, these depressions are not of sufficient depth to allow soil or other material to accumulate and lodge therein and interfere with the function of the club head. I prefer to use a metal plate to receive the depressions, but any suitable material that is sufficiently dense or hard to prevent the edges of the depressions from wearing rough may be used.

I claim as my invention:

1. A golf club having a ball-striking face provided with a series of recesses or depressions therein, the club face having flattened areas between such depressions for contact with the surface of the ball, a suction being formed between the ball cover and the walls of said depressions and preventing skidding or sliding of the ball thereon when the ball is flattened by the impact of the club face.

2. A golf club having a ball-striking face provided with a series of socket-like depressions or recesses extending into the club face and spaced apart in the surface of such face, the edges of said depressions contacting with the ball cover and preventing skidding or sliding of the ball thereon when it is flattened by contact with the club.

3. A golf club having a ball-striking face provided with a series of circular socket-like depressions or recesses extending into the club face and spaced apart in the surface of such face, the edges of said depressions contacting with the ball cover and preventing skidding or sliding of the ball thereon when it is temporarily flattened by contact with the club face.

4. As a new article of manufacture, a golf club head having a metallic striking face provided with a group of depressions or recesses extending into the club head and forming a series of suction pockets and preventing sliding or skidding of the ball thereon when struck and flattened by the club.

In witness whereof, I have hereunto set my hand this 21st day of May 1923.

WILLIAM KIDD.
